CLAIM

The ornamental design for interchangeable fashion shoe, as shown and described.

DESCRIPTION

FIG. 1 is a perspective view of an interchangeable fashion shoe showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line is included for the purpose of illustrating environmental structure and forms no part of the claimed design.
